UNITED STATES PATENT OFFICE.

ENOS B. CADE, OF PORTLAND, OREGON, ASSIGNEE TO AMERICAN LIQUID METER COMPANY, OF PORTLAND, OREGON, A CORPORATION OF WASHINGTON.

METER FOR FLUIDS.

Application filed November 15, 1921. Serial No. 515,197.

To all whom it may concern:

Be it known that I, ENOS B. CADE, a citizen of the United States of America, and resident of the city of Portland, county of Multnomah, and State of Oregon, have invented certain new and useful Improvements in Meters for Fluids, of which the following is a specification.

My invention relates to fluid meters of the type wherein a piston, reciprocable in a cylinder and actuating control valves by its movement, forms the metering element.

An important object is the simplification of such meters and the production of a meter which will be compact, easily operable and accurate.

Further objects are to provide in such a fluid meter means for controlling and locking the valves in certain positions, and to provide improved means for releasing the valves when the metering member has reached the end of its stroke.

Another object is to provide means whereby the point of release of the valve may be adjusted.

My invention comprises those novel parts and combinations thereof which are shown in the accompanying drawings, described in the specification and particularly defined by the claims terminating the same.

In the accompanying drawings I have shown my invention in the form which is now preferred by me.

Figure 1 is a section through my meter, taken on a horizontal plane.

Figures 2 and 3 are, respectively, sections on lines 2-2 and 3-3 of Figure 1.

My piston is of the general type described above, the present form comprising a cylinder 1, closed by two heads 10, the cylinder and heads having intake passages 11 and exhaust passages 12, and a piston 2 reciprocable within the cylinder to form the metering element. Control valves 3, of which I have shown one at each end, by their reversal afford communication alternately between the intake passage 11 or exhaust passage 12 and its respective end of the cylinder.

The valves 3 I have shown as tubular valves having the intake ports 31 registering with intake passages 13 in the fixed bushing 15, and having exhaust ports 32 registerable with exhaust passages 14 in the bushing 15. The two valves are secured upon opposite ends of the rod 33, the valves being axially

aligned. A spring 35 is interposed between each valve and the piston 2 and is compressible as the piston advances, and upon release of the valve holding means to be later described, operates to reverse the position of its respective valve 3 and the valve controlling mechanism.

The valve controlling mechanism includes, for each valve, one or more dogs 4, of which I have shown two for each valve, these being pivoted in the cylinder head 10, or in a cap 16 secured therein. These dogs are interposed between the valve 3 and a pin 5 which extends coaxially of the valve, and preferably lie within the confines of the valve. The pin 5 may be provided with an enlarged head 50, and this head is engageable by cam surfaces 45 on the dogs 4. The dogs are also provided with cam surfaces 43 which are engageable with the outer end of the valve 3. The pin 5 is wholly independent of the dogs 4, whereby it may be adjusted, and whereby parts may be easily removed for inspection or repair.

The pin 5 is reciprocable relative to the rod 33. The rod may have a socket 36 in each end, this socket to receive the inner end of the pin 5. The rod in this case is also provided with a transverse slot 37, through which projects the arms 53 of a cross head which is secured upon the pin 5. Preferably the cross head is threaded upon the pin so as to be adjustable thereon. I provide also a spring 52 which tends always to retain the pin 5 retracted within the socket 36 of the rod 33.

As the piston 2 advances toward one end, toward the right in Figure 1, its first action upon nearing the end of its stroke is to compress the valve-actuating spring 35. This pressure, transmitted to the outer end of the valve and acting upon the cam surfaces 43 of the dog, tends to throw the dogs inward. The head 50, however, is in position to restrain the dogs. As the piston's advance continues, its hub 20 engages the arms 53 of the cross head. The pin 5 and cross head being secured together, the pin is moved axially outward, the rod 33 being held stationary and the spring 52 being compressed. When the head 50 of the pin has moved sufficiently to leave the dogs 4 unsupported, the cam surface 45 of the dogs will ride down the inner side of the head 50, being urged in this direction by the 110

pressure of the spring 35 transmitted through the valve 3, as noted above, the latter acting upon the cam surface 43 of the dogs. This permits partial closure of the valve 3, and when the dogs have moved inward sufficiently to leave the end of the valve unsupported by the cam surface 43, the action of the spring 35 will complete the movement of the valve 3, reversing it, and reversing as well the valve at the opposite end which is connected thereto through the rod 33. Preliminary partial closure of the valve decreases the distance to be travelled finally, and consequently the time of closure, greatly increasing the meter's accuracy at high speeds.

Reversal of the valve at the opposite end causes the subsequent movement inward of the pin 5 at this end, through the medium 20 of the resilient connection of the cross head arms 53 and rod 33. When the valve is in its reversed position the dogs 4 will be thrown outward into valve-holding position and the head 50 will be moved into position 25 to lock the dogs thus. Upon reversal of the valves the piston reverses its direction of movement and the operation is repeated at the opposite end.

If it is desired to adjust the point of reversal of the valves this may be accomplished by removing a small plug 19 from the cap 16 and inserting a screw driver into a slot 51 in the end of the head 50. By turning the pin 5 in one direction or the other the position of the cross head 53 is adjusted relative to the valve 3. This varies the position of the head 50 relative to the dogs 4 and thus controls the point of reversal of the piston 2 and the valves.

40 What I claim as my invention is:

1. In a fluid meter including a cylinder, a piston reciprocable therein, and a control valve, the combination therewith of valve controlling means comprising dogs engageable with the valve to hold it in exhaust position, a pin independent of an engageable with said dogs to lock them in valve-holding position, said pin being engageable by the piston as it advances to release said dogs, 45 and means operable upon release of said dogs to reverse the valve.

2. In a fluid meter including a cylinder, a piston reciprocable therein, and a control valve, the combination therewith of valve controlling means comprising dogs engageable with the valve to hold it in exhaust position, a pin independent of and engageable with said dogs to lock them in valve-holding position, said pin being engageable 55 by the piston as it advances to release said dogs, means operable upon release of said dogs to reverse the valve, the valve and valve-controlling means being duplicated at the opposite end of the cylinder, the duplicate 60 valves being reversely positioned, and a rod connecting the valves at opposite ends of the cylinder.

ing reversely positioned, and a tension member connecting the valves at opposite ends of the cylinder.

3. In a fluid meter including a cylinder, a piston reciprocable therein, and a control valve, the combination therewith of valve controlling means comprising dogs engageable with said valve to hold it in exhaust position, a pin having an enlarged head engageable with said dogs to throw them outward into valve-holding position and to lock them thus, said pin being movable by the piston in its advance to release said dogs, and means operable upon release of said dogs to reverse the valve.

4. In a fluid meter including a cylinder, a piston reciprocable therein, and a control valve, the combination therewith of valve controlling means comprising dogs engageable with said valve to hold it in exhaust position, pin having an enlarged head engageable with said dogs to throw them outward into valve-holding position and to lock them thus, said pin being movable axially of the cylinder by the piston as it advances to release said dogs, a spring compressible by the piston's advance and operable upon release of said dogs to reverse the valve and said dogs.

5. In a fluid meter including a cylinder, a piston reciprocable therein, and a control valve at one end thereof, the combination therewith of valve controlling means comprising dogs engageable with the valve to hold it in exhaust position, a pin independent of and engageable with said dogs to lock them in valve-holding position, a spring engaging said pin and tending to hold it in locking position, said pin being engageable by the piston as it advances to release said dogs, and means operable upon release of said dogs to reverse the valve and valve-controlling means, the valve and valve-controlling means being duplicated at the opposite end of the cylinder, the duplicate 100 members being reversely positioned, and a rod connecting the valves at opposite ends of the cylinder.

6. In combination in a fluid meter, a cylinder having axially aligned inlet and exhaust ports at each end, a piston reciprocable in said cylinder, a tubular valve for the ports at each end and reversible in position, said valves at opposite ends being reversed in position, a rod to which both of said valves are secured, the ends of said rod having an axially-extending socket and a transversely-extending slot, and duplicate valve-operating and controlling mechanisms for each end of the cylinder, each comprising dogs engageable with the valve to hold it in exhaust position, a pin projectible from said socket in the end of the rod and engageable with said dogs to lock them in valve-holding position, a cross-head secured 115 120 125 130

upon said pin and having arms projecting through said slot in the rod into the path of the piston to be engaged to release the dogs by the piston's advance, and means 5 operable through the advance of the piston for reversing the positions of said valves and dogs.

7. In combination in a fluid meter, a cylinder having axially alined inlet and exhaust ports at each end, a piston reciprocable in said cylinder, a tubular valve for the ports at each end and reversible in position, said valves at opposite ends being reversed in position, a rod to which both of 10 said valves are secured, the ends of said rod having an axially-extending socket and a transversely-extending slot, and duplicate valve-operating and controlling mechanisms for each end of the cylinder, each 15 comprising dogs engageable with the valve to hold it in exhaust position, a pin projectable from said socket in the end of the rod and engageable with said dogs to lock them in valve-holding position, resilient 20 means tending to retract the pin into its socket, a cross-head secured upon said pin and having arms projecting through said slot in the rod into the path of the piston to be engaged to release the dogs by the piston's advance, and means operable through 25 the advance of the piston for reversing the positions of said valves and dogs.

8. In combination in a fluid meter, a cylinder having axially alined inlet and exhaust ports at each end, a piston reciprocable in said cylinder, a tubular valve for the ports at each end and reversible in position, said valves at opposite ends being reversed in position, a rod to which both of 30 said valves are secured, the end of said rod having an axially-extending socket and a transversely-extending slot, and duplicate valve-operating and controlling mechanisms for each end of the cylinder, each comprising 35 dogs engageable with the valve to hold it in exhaust position, a pin projectable from said socket in the end of the rod and engageable with said dogs to lock them in valve-holding position, a cross-head secured 40 upon said pin and having arms projecting through said slot in the rod into the path of the piston to be engaged to release the dogs by the piston's advance, a spring 45 engaging said cross-head arms to retain the pin projected into its socket, and means operable through the advance of the piston for reversing the positions of said valves and dogs.

9. In a fluid meter including a cylinder,

a piston reciprocable therein, a control valve 60 at each end of the cylinder, and a rod connecting the valves which are at opposite ends of the cylinder, valve controlling mechanism for each valve comprising a pin reciprocable relative to said rod and 65 having a head on its outer end, dogs interposed between said head and the valve and engageable with the valve to hold it in exhaust position, the head then engaging the dogs to lock them in valve-holding position, a cross-head adjustably secured upon the inner end of said pin, said cross-head being engageable by the piston as it advances to thereby release said dogs, and means operable upon release of the dogs 70 to reverse the valve and valve controlling mechanism at each end of the cylinder.

10. In a fluid meter including a cylinder, a piston therein, a fluid control valve for each end of the cylinder and means connecting said valves to move together, the combination therewith of a spring compressible by the piston in its advance to close the valve, a dog engageable with the valve by inclined surfaces to hold the valve open, 80 and a dog locking member movable immediately following actuation of the valve to engage the dog in valve-holding position and movable by the piston to release the dog.

11. In a cylinder and piston meter, a spring-actuated reciprocating valve, a valve holding dog, said dog and valve having inclined holding surfaces, and a dog-retaining member controlled in its position by movement of the meter piston.

12. In a meter including a cylinder and a piston therein, a reciprocating fluid controlling valve, a valve actuating spring between the valve and piston, a valve holding dog, said dog and valve having inclined engaging surfaces, and a dog retaining member adapted to hold the dog in valve-open position, and means for shifting said dog retaining member to release the dog.

13. In a meter including a cylinder and a piston therein, a reciprocating fluid controlling valve, a valve actuating spring between the valve and piston, a valve holding dog, said dog and valve having inclined engaging surfaces, and means for retaining the dog in valve-holding position, said retaining means being shifted to release the dog by the movement of the piston at the end of its stroke.

Signed at Seattle, King County, Washington, this 5th day of October 1921.

ENOS B. CADE.
